UNITED STATES PATENT OFFICE.

FRANK E. WOCHEL, OF NEW YORK, N. Y.

SANITARY MILK-BOTTLE HOLDER.

1,341,607.

Specification of Letters Patent.

Patented May 25, 1920.

Application filed April 19, 1919. Serial No. 291,333.

To all whom it may concern:

Be it known that I, FRANK E. WOCHEL, a citizen of the United States of America, residing at New York city, in the county of 5 New York and State of New York, have invented new and useful Improvements in Sanitary Milk-Bottle Holders, of which the following is a specification.

This invention relates to bottle holders 10 and more particularly to a holder or retainer for milk bottles.

The primary object of the invention is the provision of a milk bottle holder which is adapted to be secured to the frame or 15 jamb of a door and which is provided with an open side that is normally closed or obstructed when the door is shut.

Another object of the invention is the provision of a device of the class described 20 which comprises a plurality of telescopic members slidably associated with each other whereby the device may accommodate one or more bottles when in its adjusted positions.

25 A further object of the invention is the provision of a structure of the class described which is provided with means for retaining the bottles within the casing to prevent the removal of the same from the 30 open bottom of the device.

A still further object of the invention is the provision of a structure of the class described provided with locking means for locking the members in their adjusted positions.

With these and other objects in view the invention resides in the novel construction, combination and arrangements of parts fully described and pointed out in the following description and claims and illustrated in the accompanying drawings, in which—

Figure 1 is a perspective view of the holder in its applied position to the frame 45 of a door.

Fig. 2 is a perspective view of the lower member of the casing.

Fig. 3 is a perspective view of the upper member of the casing.

50 Fig. 4 is a horizontal fragmentary sectional view through a door frame showing the device applied thereto.

Fig. 5 is a detail fragmentary sectional view of the means for supporting the bottle 55 within the casing.

In the drawing A designates the door

and B the door frame to which is attached the milk bottle holder C which comprises a pair of telescopic members 10 and 11, the lowermost member 10 comprising the side 60 walls 12 and front wall 13. Provided at the lower end of the casing 10 and riveted thereto is a substantially square reinforcing band 14, in the corners of which are riveted or otherwise secured a plurality of U shaped 65 members 15 in which are pivoted the spring pressed lugs 16. The lugs are adapted to be swung in an upward position only and the springs 17, with which they are provided cause them to normally assume a horizontal position, thus providing a retaining and supporting means for the bottles. It will be understood from this construction that a bottle or bottles may be readily inserted into the casing through the lower 70 end but are prevented from being removed therefrom after once in place except through the open sides of the members 10 and 11 when the door is opened. One of the side walls 12 of the member 10 is provided with 75 a plurality of key hole slots 18 and pivoted adjacent each of said slots is a hook member 19. The door frame A is provided with the headed members 20, which are adapted to rest in the key hole slots 18 when the holder 80 is placed in position on the door frame. The upper member 11, is of substantially the same construction as the lower member 10, but in addition thereto is provided with a top or cover wall 21, and is further provided at its lowermost end at one side thereof with a depending lug 22. One of the side walls of the casing 11, is provided with a series of key hole slots 23, the lower one being preferably provided in the lug 90 22. The upper member 11, is adapted to telescope the lower member 10 and each of the members adjacent its lower end is provided with a guard strip 24, which prevents the bottle from accidentally falling 95 out of the holder when the door is opened.

In operation of the device the members of the casing are adjusted to accommodate either one or two bottles as the case may be, by telescoping the members and registering 105 the key hole slots 23 and 18. The casing is then attached or secured to the frame of the door by placing the side of the members provided with the key hole slots against the sill so that the headed members 20 enter 110 the key hole slots therein. The hook members 19 are then swung into active engage-

ment with the headed member 20 in order to lock the device in its adjusted position. It will thus be seen that while I have provided a milk bottle holder which prevents 5 the removal of the bottle therefrom by an unauthorized person, I have also provided a device which automatically informs the vendor the number of bottles desired.

While I have shown and described a simple and preferred form of carrying the invention into practice, I do not desire to be limited to the exact details therein exhibited but wish to have it understood that such changes and alterations as fall within the 15 scope of the appended claims may be resorted to when desired.

What I claim as new is:

1. A bottle retainer comprising an adjustable casing composed of a plurality of 20 telescopic members, substantially U shaped in cross section, the uppermost member be-

ing closed at the top, retaining and locking means pivoted within the lowermost member near its lower end and means for locking the casing in its adjusted positions, said 25 means comprising slotted portions of the members and hooks pivoted relative to said slots, in combination with means adapted to be secured to the frame of the door.

2. A bottle retainer, comprising an end-wise extensible casing composed of telescopic members, substantially U-shaped in cross-section, the uppermost member being closed at the top, means in the lowermost member to permit the upward insertion and 35 prevent the downward withdrawal of a milk bottle, and means to secure the casing in its extended and contracted states to a door frame.

In testimony whereof I affix my signature. 40

FRANK E. WOCHEL.
